UNITED STATES PATENT OFFICE.

ALFRED A. FISHER AND ALBERT HART, OF SAN FRANCISCO, CALIFORNIA,
ASSIGNORS TO THE PACIFIC TUCKING AND MANUFACTURING COMPANY,
OF SAME PLACE.

TUCKER ATTACHMENT FOR SEWING-MACHINES.

SPECIFICATION forming part of Letters Patent No. 278,422, dated May 29, 1883.

Application filed April 21, 1882. (No model.)

To all whom it may concern:

Be it known that we, ALFRED A. FISHER and ALBERT HART, of the city and county of San Francisco, State of California, have invented an Improved Tucker Attachment for Sewing-Machines; and we hereby declare the following to be a full, clear, and exact description thereof.

Our invention relates to a tucker attachment for sewing-machines, and particularly to certain new and useful improvements upon a tucker attachment for which we applied for Letters Patent of the United States, July 27, 1881, and which was allowed February 27, 1882, and to the specification and drawings of which we hereby specially refer.

These improvements consist generally in the arrangement of parts and their construction, having in view the provision of a tucker attachment more nearly approaching perfection than that to which we have referred; and they consist particularly in a novel means of adjusting the base-plate and the lower or under guard, and in the particular construction of said guard and its underlying tuck-securing plate; also, in a novel means for regulating the width of the tuck-guiding slot, and in a novel adjustable tuck guard or support within the slot; also, in a novel means for adjusting the upper guard, and in adjustable attachments thereto for guiding the goods to the tucker, and in the means by which this is accomplished.

For a more particular explanation reference is hereby made to the following description, and to the accompanying drawings, in which—

Figure 1 is a perspective view of the tucker, showing the goods in process of tucking. Fig. 2 is a front elevation of the tucker. Fig. 3 is a perspective view of the tucker with guard open. Fig. 4 is a side elevation of the end of the tucker next the sewing-machine. Fig. 5 is a section through tuck-guiding slot *c*. Fig. 6 is a plan showing gage and swivel of upper guard. Fig. 7 is a plan of the clutch-plate. Fig. 8 is a section through line 1 2 on Figs. 2 and 3. Fig. 9 is a section through line 3 4 on Fig. 6. Fig. 10 is a section through line 5 6 on Fig. 7.

A represents generally the operative parts of any sewing-machine, showing the needle, presser-foot, &c.

C represents the base-plate of the tucking attachment. This is secured to the top of the machine by means of a set-screw through a slot, *a*.

D is the inclined plow-shaped transverse piece secured upon the top of the base-plate.

E is the piece upon the base-plate having an inclination similar to that of *D*. It is secured to plate *C* by means of a slot, through which a stationary screw, *b*, passes into said plate. It is adapted to move upon said plate to vary its distance from piece *D* by means of an adjusting-screw, *b'*, which passes through its side next to piece *D* into said piece. Between the two transverse pieces *D* and *E* is formed the slot *c*, which may be suitably adjusted in width by operating screw *b'*, which by its movement withdraws or advances piece *E*.

d represents the guide-plate, which is attached to the inner side, near its lower end, of piece *E*, within slot *c*, and which lays the tuck flat which travels in slot *c*.

F represents the guide or support for the tuck. It consists of a strip of metal, the base of which is straight and lies on base-plate *C*. Its top is inclined upwardly toward the rear. It has a slotted top guide, *f'*, to direct the tuck, and a horizontal slot, *f*. It is placed between pieces *D* and *E* in slot *c*, and the adjusting-screw *b'* passes through its slot *f*. By moving it back or forth across the base-plate *C*, the distance between its inclined top and the top of pieces *D* and *E* may be varied for different widths of tuck which travel in slot *c*. Thus by moving it forward the distance is decreased, and vice versa. It is held in position by the approaching edges of the pieces *D* and *E*, and its top has a similar inclination to said pieces.

G is the hinge upon the outer end of piece *E*, with its side guides, *g*, in which the end or shank of the upper guard, *H*, fits. This guard has a wide cross end, *h*, turned upward at right angles, and is provided with vertical slots *h'*.

H' is an angled guard, the upright side of which fits against the upturned end *h*, and is

secured thereto by screws h^2 passing through slots h' , thus being firmly secured to the upright part of the guard H . The shank of the guard H has a slot, d' , the end of which is enlarged, and is adapted to fit over a thumb-screw, e , secured in piece E . The operation of the guard H is similar to that explained by us heretofore. By means of its hinge it may turn down upon and slip forward on piece E .

10 In order to adjust its position in slipping forward, when desirable, we have the sliding stop-plate e' , secured by a screw, e^2 , its end being adapted, when set to proper position, to come in contact with the thumb-screw e , and thus to limit the movement of guard H toward the slot e , where the goods are passing. The upturned cross end h of guard H is continued upon a level below the lower end of piece E , and is slotted, as shown. The guard H is it 15 self continued upon a level, and supports a sliding guide, Z , having a slot and secured by a screw, z . This guide is adapted to slide forward through the slotted end of h , and serves as a continuation of the presser-foot of the machine when such is necessary by reason of the movement of the tucker to suit various tucks. The guard H is also continued above, and a sliding guide-plate, Z' , secured by a screw, is 20 adapted to slide under it, to hold the goods close against the under guard and direct them to the slot e . The other end of the base-plate C fits into side guides under a plate, C' , and has a cross-guide, c' , above said plate, fitting through its slotted end, as shown. Through 25 the cross-guide c' a screw, c^2 , passes. This screw is the end of a rod passing in a suitable channel to the end of plate C' , where it is provided with a pinion, i , with which meshes a gear, i' , operated by a thumb-wheel, I' , as shown. By moving this thumb-wheel the screw-rod c^2 moves the base-plate C in the direction of its length. By loosening the thumb-screw through the slot a , which secures the base-plate to the sewing-machine, said base-plate may thus be moved to adjust the position of the slot e with reference to the needle. The plate C' has attached to its end an upper plate, I , which is inclined in about the same manner as the pieces D and E . It extends 40 over plate C' , and has upon its inner end a pivot-pin, k .

50 J represents the under guard. It consists of a light open frame having a cross-head, j , upon its inner end. The outer end of said under guard has a longitudinal slot, 15, through which projects from plate I a screw-stud, k , provided with a nut, and affording, with slot 15, means for an additional longitudinal adjustment of J . On the same screw-stud, k , passing through hole 5 and 55 between the end of J and the plate I , is a turn-plate, m , provided with a notch, k' , which brings up against a stud, k'' , when m and I are in position to be secured together by the spring-bolt m' , secured to I and adapted to enter a recess in said turn-table plate. A thumb-nut, j' , fits screw l' and secures the bearing to the

guard. The guard and bearing fit over the pivot-pin k , and a set-screw secures it. A clutch-plate, m' , sliding in guides m^2 upon the inclined plate I , fits its end into the notched end of the bearing-plate m and keeps the guard J straight. The clutch-plate m' is held in engagement by a spring, m^3 , within a recess in plate I . By moving and holding the clutch-plate m' back the guard J may be swung around 75 or turned out of the way. By loosening thumb-nut j' the guard J may be moved in the direction of its length to adjust the distance of its cross-head j from the slot e .

K is the tuck-securing plate under guard J , 80 toward its inner end. This has a cross-head, q , with a turned-down edge or lip adapted to fit within the slot e its entire length. The adjustment of this plate is accomplished by providing its upper side with beveled flange-guides q' , fitted upon and supported by the correspondingly-beveled edges of the guard J . The outer end of the plate K is provided with a screw-pin, q^2 , which fits through a slot, o , in the guard J , and is secured by a nut. 90

In order to provide for the setting of guard J when it becomes necessary to turn it somewhat upon its pivoted end, and still to keep its cross-head straight with the slot e and its tuck-securing plate K in such position as to 95 keep its lip q within the said slot, we make the guard in two sections, the joint being at Y' , whereby a secondary adjustment is had of the upper plate, and the adjustment made with great nicety. Here two screws secure the two 100 sections. When loosened the inner section, carrying the plate K , may be always kept straight no matter what position or inclination the whole guard may be made to assume.

The operation of the tucker upon the cloth, 105 when fed to it in the manner we shall presently explain, is precisely the same as we have explained in our previous specification, the changes herein made being simply to effect a better result. The goods are folded around the cross-head j and extend away from the machine, one fold being under and the other above the guard J . The previous tuck (which is on the under fold) travels in the slot e . The cross-head j makes the tuck, and its lateral 110 adjustment varies its width. Thus the under guard, J , is adjusted in the direction of its adjustment varies its width. Thus the under guard, J , is adjusted in the direction of its length so that its cross-head shall extend beyond the needle a distance equal to the width of the tuck to be made. The upper guard, H , 115 is folded down upon and secures the cloth, its upturned cross end fitting against the cross end of the guard J . The angled guard H' may be adjusted to provide for the thickness of the material, which by passing under it is suitably guided.

When the tuck to be made is very wide, and the goods in passing from under the needle extend to one side of the presser-foot, the sliding guide-plate Z may be adjusted over the 120 goods and properly direct them.

To prevent the goods from sagging down

after leaving the frame, and keep them closely up against the cross-head *j* of guard *J*, and direct the previous tuck into slot *c*, the guide-plate *Z'* above may be pushed out under them, 5 and thus support and guide them.

To prevent the guard *H* from being adjusted so closely to the cross-head of guard *J* that it would have a tendency to bind the goods, and thus impede their passage, the stop-plate 10 *e'* may be suitably set, as explained.

After the first tuck is completed it is made to travel in the slot *c* and furnish a guide for the width between it and the next tuck.

The adjustment of the base-plate and of the 15 guard *J* to fix the position of the slot *c* with regard to the needle, and to cause the said guard, with its plate *K*, to conform to the changed position of the base-plate, is accomplished by the 20 means herein described, and for the purpose heretofore explained in our previous specification. In order to accurately determine these 25 adjustments, we have a gage, *r*, consisting of a number of lines upon the plate *C'*. The point of the cross-guide *c'* of the main plate *C* is utilized as a pointer. The other gage is marked *t* upon the end of the guard *J*, and to it a pointer, *s*, secured by the thumb-nuts *j'* and the nut fitting pivot-pin *k*, is directed.

Although we have heretofore spoken of the 30 space between the transverse pieces *D* and *E* as a "slot," *c*, it is obvious that it might be a groove or any suitable channel for directing the tuck which travels in it.

We have in our previous specification explained the necessity for and the operation of a suitable frame from which and by which the 35 goods are directed or fed to the tucker. Our improvement in this respect consists in a frame by which an endless band of goods is fed to the device, whereby we are enabled to continue the tucking process without having to remove the cloth after each tuck, as we have hitherto been compelled to do. We have thus effected 40 a new method of accomplishing the tucking process, by means of which we can without interruption tuck a large piece or bolt of cloth. The present tucker and the means for feeding the goods to it are jointly adapted to produce 45 the result.

50 *P* is the top of the table, having an elevated longitudinal bar or portion, *x*, the upper surface of which is on a level with the upper surface of the plate of the sewing-machine, said plate extending to one side and resting against the said raised portion *x* of table *P*, being secured to the base-plate of the tucker by means of ears and screws 14. *P'* are the legs of the table. In the front of the table is journaled a roller, *Q*. Upon its back are secured socket-bearings *R*, in which fit rods *R'*, adapted to be 55 vertically adjusted therein by means of a thumb-nut under the table. In the tops of these adjustable rods is journaled a rod, *r'*, secured to the directing-board *S*. This board continues the inclination of the transverse pieces *D* and *E* of the tucker, its lower edge

approaching nearly to the top of the inclined tuck-support *F*, and thence inclining upwardly to the rear, as shown. In its upper end is journaled a roller, *S'*, having a flange upon its 70 inner end. This roller may be journaled, as shown, in any of the series of notches made in the side pieces of board *S*.

T is a brace pivoted to the back of the table *P*, its other end being engaged in a rack-bar, 75 *p*, under the board *S*. This supports the said board and provides for its change of inclination.

V represents a tension-roller suspended under the board, which may be used for very 80 light stuff. The object of this construction is to provide for the adjustment of the directing-board as follows: The inner edge of the board is very nearly in a line with the cross end *j* of guard *J* of the tucker, and the flange upon the 85 inner edge of roller *S'* defines the limit or fold of the goods. When the guard *J* is moved to make a different width of tuck, as explained, the directing-board must also be moved laterally to keep its position with reference to said 90 guard. This it can do by reason of the rod *r'*, journaled in the tops of the rods *R'*, because said rod can be moved laterally when desired. It becomes necessary to adjust the vertical position of the directing-board when a wide tuck 95 is being made, so as to support the goods in a position high enough to direct the tuck within slot *c*. This is accomplished by the vertically-adjustable rods *R'*. The inclination of the board is changed by the brace *T* to cause it 100 to conform to the inclination of the pieces *D* and *E* after said board has been vertically adjusted.

Let *W* represent the goods. This is made in an endless band by properly securing the 105 two ends. It passes over roller *S'*, down the directing-board *S* to the tucker, over roller *Q*, and under the table, up again to roller *S'*. When the tension-roller *V* is needed it may be passed over it. As the tucking progresses 110 the part tucked is turned under, and when once started will continue. The cloth advances as the machine draws it, and the tuck is continuous, as are the threads of a screw, for the portion or part of tuck previously made is 115 constantly passing through the slot *c*, and the cross-head *j* of guard *J* always folds it over until the piece of goods is finished in one continuous tuck.

If we should not desire to feed the goods to 120 the tucker in an endless band, we could fold the bolt upon a table under the board *S*, and carry it up over the roller *S'* and deposit it in front.

Having thus described our invention, what 125 we claim as new, and desire to secure by Letters Patent, is—

1. In a tucking attachment for a sewing-machine, the base-plate *C*, secured to the sewing-machine and carrying the tucking devices, said 130 base-plate having upon its outer end a cross-piece, *c'*, in combination with the stationary

- plate C', with its slotted end, in which the cross-piece c' fits, and the adjusting screw-rod c², fitting through said cross-piece, substantially as and for the purpose herein described.
5. 2. In a tucking attachment for a sewing-machine, the combination of the telescopic base-plate C, stationary guide-plate C', inclined bearing I, and the swinging under guard, J, substantially as herein described.
10. 3. In a tucking attachment for a sewing-machine, the inclined bearing-plate I and the swinging guard J, in combination with the underlying bearing-plate m, having the notch k' and the spring clutch-plate m', substantially as and for the purpose herein described.
15. 4. In a tucking attachment for a sewing-machine, the swinging guard J, having a cross-head, j', said guard being made in two sections, having an adjustable point, Y', substantially as and for the purpose herein described.
20. 5. In a tucking attachment for a sewing-machine, the under guard, J, in combination with the adjustable tuck-securing plate K, fitted under and supported by said guard by means of the beveled flange-guides q', substantially as and for the purpose herein described.
25. 6. In a tucking attachment for sewing-machines the base-plate C, having a transverse inclined piece, D, in combination with the transverse inclined piece E, said piece E being adapted to move to or from piece D by means of its slot fitting over screw b, and the adjusting-screw b', passing through said pieces D and E, substantially as and for the purpose herein described.
30. 7. In a tucking attachment for sewing-machines, the combination of the inclined pieces D and E and the adjustable inclined tuck-supporting piece F between them, substantially as and for the purpose herein described.
35. 8. In a tucking attachment for sewing-machines, the upper guard, H, with its upturned cross end h, having vertical slots h', in combination with the angled guide-plate H', rendered vertically adjustable by means of screws h² passing into it through said slots, substantially as and for the purpose herein described.
40. 9. In a tucking attachment for sewing-ma-
- chines, the sliding upper guard, H, in combination with the guiding-screw e and adjustable stop-plate e', substantially as and for the purpose herein described.
45. 10. In a tucking attachment for sewing-machines, the upper guard, H, in combination with the upper and lower sliding plates, Z and Z', substantially as and for the purpose herein described.
50. 11. The improvement in tucking goods, consisting in tucking them in an endless band fed in a spiral line to a tucking device, whereby an uninterrupted and continuous tuck may be made, substantially as herein described.
55. 12. In combination with a sewing-machine and a tucking device, a vertically and laterally adjustable directing-board, S, or table, whereby the goods may be fed to the tucker with precision, substantially as herein described.
60. 13. In combination with a sewing-machine and a tucking device, the inclined directing-board S, having a rod, r', journaled in the tops of the vertically-adjustable rods R', and supported by the adjustable brace T, substantially as herein described.
65. 14. In combination with a sewing-machine and the tucking device herein described, the table P, with its roller Q, socket-bearings R, and vertically-adjustable rods R', the inclined directing-board S, with its rod r', adjustable brace T, and roller S', substantially as and for the purpose herein described.
70. 15. In combination with a sewing-machine and a tucker having the transverse inclined pieces D and E, forming between them a slot, e, in which and over which the goods are directed to the needle, the inclined directing-board S, with its roller S', rod r', and adjustable brace T, and the table P, with its roller Q, socket-bearings R, and vertically-adjustable rods R', substantially as and for the purpose herein described.
75. In witness whereof we hereto set our hands.
